CLAIM

The ornamental design for a container lid, as shown and described.

DESCRIPTION

FIG. 1 is a first perspective view of the container lid design;
FIG. 2 is a second perspective view thereof;
FIG. 3 is a first side view thereof;
FIG. 4 is a second side view thereof;
FIG. 5 is a third side view thereof;
FIG. 6 is a fourth side view thereof;
FIG. 7 is a top view thereof;
FIG. 8 is a bottom view thereof; and,
FIG. 9 is a perspective thereof in an alternate position of use.
The dashed lines depict portions of the container lid that
form no part of the claimed design.

1 Claim, 9 Drawing Sheets
